UNITED STATES PATENT OFFICE.

ANDREW JOSEPH BARRON, OF SAYLOR PARK STATION, OHIO, ASSIGNOR TO THE PHOENIX HORSE SHOE COMPANY, OF NEW YORK, N. Y., A CORPORATION OF ILLINOIS.

SPRING SUPPORT OR HANGER.

Application filed January 30, 1925. Serial No. 5,852.

To all whom it may concern:

Be it known that I, ANDREW J. BARRON, a citizen of the United States, residing at Saylor Park Station, in the county of Hamilton 5 and State of Ohio, have invented certain new and useful Improvements in Spring Supports or Hangers, of which the following is a specification.

The object of my invention is to provide 10 an improved front hanger or support for ordinary semi-elliptical side springs and especially for the side-springs of a platform-spring construction adapted and intended more particularly for use in connection with automotive trucks of the Ford 15 type.

More specifically, the object is to provide 20 a hanger or support, of the character noted, which is constructed to relieve the chassis channels of undue strain by providing means for tying the hanger to the sub-sill.

A subsidiary object is to provide a hanger or support which, while simple in construction, presents the requisite strength against 25 breakage or distortion.

The invention is fully disclosed in the accompanying drawing, in which the application of the hanger, or its installation on the automotive vehicle, is shown. Like reference-characters denote corresponding parts 30 throughout the several views. The different views of the invention shown in the drawing may be briefly described as follows:

Figure 1 is a top plan view of a portion 35 of the frame and body of an automotive truck, showing my hangers installed in position thereon;

Figure 2 is a cross sectional view, on the plane of the section line 2—2, Fig. 1, looking 40 in the direction of the arrows indicated thereon;

Figure 3 is a view in side elevation of one 45 of my hangers; and

Figure 4 is a view in end elevation thereof.

Referring, now, in detail to the drawing:

The hanger or support for each of the two side springs 1, 1 is a one-piece structure, by preference, and, for this purpose, may be 50 made as a casting, comprising a base 2, having a central, longitudinal strengthening rib or flange 3; an upstanding lug 4 at the forward end of the base and bored, as shown at 5, for the reception of a pin 6 of a shackle 7 for the forward end of the side spring 1; a

rear wall 8 at right-angles to and rising from the base 2, and provided, toward its top, with bolt-holes 12, 12 and, at its bottom, an extension 9 depending below the base 2 and having rearward-projecting, lateral lugs 10, 10, bolt-holes 12, 12 being bored through the lugs and the extension 9; side walls 13, 13 rising from the base 2 and united with the rear wall 8 and connected toward their top by a bridge 14.

In use, the hanger is disposed beneath one of the sub-sills 15 of the automotive-vehicle body, with the bridge 14 bearing against said sub-sill, and with the rear wall 8 bearing against the chassis-channel 11, 60 and with the lugs 10, 10 projected under said chassis-channel and bearing upwardly thereagainst, as shown in Fig. 2. Bolts 16 are projected through the bolt-holes 12, 12 in the rear-wall 8 of the hanger and 65 through registering bolt-holes in angles 17 disposed on the opposite side of the channel 11, and nuts 18 are tightened up on the threaded ends of the bolts. Similar bolts 19 are projected through the bolt-holes 12, 12 in the rear wall extension 9 and through 70 registering bolt-holes in the angles 17, and nuts 20 are tightened up on the threaded ends of the bolts. By means of the bolts 16 and 19 and the nuts 18 and 20, the hanger 75 is firmly clamped to or against the chassis-channel 11. U-bolts 21 pass over the sub-sills 15, 15 and through bolt-holes 22, 22 in each of the bridges 14 of the hangers, nuts 80 being screwed on the threaded ends of the U-bolts below the bridges 14, 14, whereby the hangers are supported or suspended from the sub-sills 15, 15, and undue stress and strain is taken away from the chassis-channels 11, 11. It will be noted that, if no 85 means were provided for suspending or supporting the hangers from the sub-sills 15, 15, the entire strain and stress of the hangers would be upon the channels 11, 11, which is 90 objectionable.

Having thus fully described my invention, what I claim as new and desire to secure by Letters-Patent of the United States is:

1. The combination, in an automotive vehicle, of a longitudinal chassis-channel, a longitudinal sub-sill, a side spring, and a support or hanger supporting the front end of said spring and comprising a casting having a base, a rear wall rising therefrom 105

100

105

110

and bearing against said chassis-channel, two side walls also rising from said base and united to said rear wall, a bridge connecting said side walls and bearing against the bottom of said sub-sill, and means passing through said bridge for suspending said support from said sub-sill.

2. The combination, in an automotive vehicle, of a longitudinal chassis-channel, a longitudinal sub-sill, a side spring, and a support or hanger supporting the front end of said spring and comprising a casting having a base, a rear wall rising therefrom

and bearing against one side of said chassis-channel, means passing through said rear wall for securing said support against said chassis-channel, two side walls rising from said base, a bridge connecting said side walls and bearing against the bottom of said sub-sill, and means passing through said bridge for suspending said support from said sub-sill.

In testimony whereof, I hereunto affix my signature.

ANDREW JOSEPH BARRON.
